UNITED STATES PATENT OFFICE.

DANIEL HIGHAM, OF BRIDGEPORT, CONNECTICUT, ASSIGNOR TO HIGHAM-PHONE COMPANY, OF JERSEY CITY, NEW JERSEY, A CORPORATION OF NEW JERSEY.

PHONIC APPARATUS.

SPECIFICATION forming part of Letters Patent No. 783,750, dated February 28, 1905.

Application filed December 12, 1904. Serial No. 236,609.

To all whom it may concern:

Be it known that I, DANIEL HIGHAM, of Bridgeport, Connecticut, have invented a new and useful Improvement in Phonic Apparatus, which invention is fully set forth in the following specification.

This invention relates to phonic apparatus employing friction means for reproducing sound vibrations with increased energy, as described in my United States patent dated July 16, 1901, No. 678,566. In such employment of friction means it has been found difficult to construct and adjust the same in such manner as to exert and maintain the desired amount of frictional force.

It is the object of the present invention to provide means whereby the friction means will automatically adjust the amount of pressure determining the frictional contact, and thereby maintain the frictional force exerted at a practically uniform amount.

The invention can best be described in connection with the accompanying drawings, in which—

Figure 1 diagrammatically represents said invention as applied to graphophonic reproducing means. Fig. 2 is a plan view of part of the apparatus shown in Fig. 1. Fig. 3 is a view in cross-section of the friction roller and shoe. Fig. 4 is a diagram illustrating another mode of carrying out the invention, and Fig. 5 represents the invention as applied to telephonic reproducing means.

In Fig. 1, 2 is a friction-roller supported by a spindle 3 and revolved in the direction of the arrow from a suitable source of motive power. 4 and 5 represent, respectively, the two parts of a friction-shoe connected together in the present instance by a small link 6. The shoe extends more than half-way around roller 2. 7 is a link connecting the part 5 to a diaphragm 8, the latter being supported by a frame 9, (shown in cross-section.) 10 is a link connecting shoe part 4 to a lever 11, hinged in the present instance at 12 and carrying a reproducing-point 13 in contact with a sound-record 14, revolved and advanced by usual

means. 15 is a swinging bearing for spindle 3, hinged upon a pin 16, and 17 is a weight to lend retarding inertia to spindle 3 and to cause the friction-roller 2 to press by gravity upon the shoe 4 5.

In Fig. 2 roller 2, spindle 3, weight 17, swinging bearing 15, and pin 16 are shown together with a coupling-socket for spindle 3, (shown in cross-section at 18,) which permits of movement of swinging bearing 15.

In Fig. 3 roller 2 and shoe parts 4 and 5 are shown in cross-section through the line *ww*, Fig. 1, from which it will be seen that roller 2 is slightly grooved or V-shaped to guide the shoe parts 4 and 5 and that shoe part 5 is much wider than shoe part 4.

In Fig. 4 similar reference-numerals indicate similar parts shown in Figs. 1, 2, and 3; but in this modification of the invention the roller 2 is revolved by spindle 3 about a fixed point or axis, while the frame 9, supporting diaphragm 8, in the present instance is made to swing upon a pin 19, and a spring 20, connecting frame 9 to a pin 21, is used to support frame 9 movably against the frictional force exerted by roller 2.

In Fig. 5 similar parts shown in Figs. 1, 2, and 3 are also indicated by similar reference-numerals; but in this application of the invention a telephone-receiver is diagrammatically represented as means for operating lever 11, and a telephone-transmitter is diagrammatically represented as means for responding to the reproduced sound-vibrations.

The operation of the friction means independently of my present invention is briefly as follows: Sonorous vibrations which are imparted to lever 11 by suitable primary vibrating means will produce through link 10 corresponding vibrations or variations in the amount of pressure exerted by shoe parts 4 and 5 upon roller 2, and thereby effect corresponding vibrations or variations in the frictional force exerted through link 7 upon suitable secondary vibrating means, substantially as described in my above-mentioned patent of July 16, 1901. To effect automatic adjust-

ment of the friction means, which is the object of the present invention, I have shown means for permitting movement to take place between the friction means and the secondary 5 vibrating means in accordance with the amount of frictional force exerted between the same. In Fig. 1 this movement is permitted to take place by means of the swinging bearing 15 supporting spindle 3 and hinged at 16, while 10 in Fig. 4 it is permitted to take place by means of the swinging frame 9, hinged at 19 and elastically supported by the spring 20.

The operation of my present invention will be readily understood, for it will be seen that 15 the frictional force exerted by the rotation of the roller 2 upon diaphragm 8 or other suitable secondary vibrating means could not vary unduly, inasmuch as an increase of frictional force would tend to move shoe parts 4 and 5 20 farther around the roller 2 in the direction of rotation by virtue of the permitted movement between the roller 2 and diaphragm 8, Figs. 1 and 4, whereby the pressure imparted through link 10 in supporting shoe parts 4 and 25 5 in frictional contact with roller 2 would be reduced, thereby checking or counterbalancing the increased frictional force, and vice versa. The automatic adjustment of the friction means is thus effected. It will further 30 be understood that the inertia of the parts, which are made movable in order to effect this automatic adjustment, will be sufficiently great to prevent interference with the vibrations in frictional force corresponding to 35 sound-waves.

The advantage of having shoe part 5 wider than shoe part 4, as shown in Fig. 3, is most noticeable with the use of a friction-roller, composed of amber or other similar material 40 When the pressure of shoe part 4 is increased by the means herein provided for automatic adjustment of the friction means, the shoe part 4 will tend to wear the friction-roller away in the middle of the groove and tend to 45 leave only the outer edges of the groove for the shoe part 5, whereby the pressure of shoe part 5 will be increased in proportion to the area of frictional surface, and, vice versa, a decreased pressure of shoe part 4 will effect a 50 decreased pressure per amount of frictional surface of shoe part 5, thus making the automatic adjustment of friction means most efficient.

It should be understood that the present invention may be applied to any kind of phonic apparatus employing a friction means and that modifications of the precise arrangement of parts herein diagrammatically represented may be made without departing from the spirit 55 and scope of the invention.

In the claims which follow the friction-roller and shoe parts will be referred to as "friction means," the vibrating means setting up sound-vibrations at the friction means as

"primary vibrating means," the vibrating 65 means responding to sound-vibrations set up by the friction means as "secondary vibrating means," the part of the friction-shoe farthest in the direction of rotation of friction-roller as the "forward part of the friction-shoe," and the receding part as "the rear part of the friction-shoe."

What is claimed is—

1. In a phonic apparatus, a primary and a secondary vibrating means, and a friction 75 means, in combination with means for permitting movement between the said friction means and said secondary means.

2. In a phonic apparatus, the combination 80 of a secondary vibrating means, a friction device, means permitting one of said parts to move toward and away from the other part as the frictional force increases or diminishes, and a primary vibrating means.

3. In phonic apparatus, a primary and a 85 secondary vibrating means, and a friction means, in combination with means permitting movement of said friction means in response to the frictional force exerted, said movement being sufficient to effect automatic adjustment 90 of the friction means, substantially as described.

4. In a phonic apparatus, the combination 95 of primary and secondary vibrating means and intermediate friction means, with means permitting movement of said friction means toward and away from said secondary vibrating means as the frictional force increases or diminishes.

5. In a phonic apparatus, the combination 100 of primary and secondary vibrating means, and intermediate friction means, one member of which rests by gravity upon the other and is supported to have freedom of movement toward and from the secondary vibrating means.

6. In a phonic apparatus, the combination 105 of primary and secondary vibrating means, and intermediate friction means comprising a friction-roller carried by a shaft which rests by gravity upon a friction-shoe constituting the other member.

7. In a phonic apparatus, a friction means including a friction-shoe whereof one part has greater frictional surface than the other 115 part thereof for the purpose described.

8. In a phonic apparatus, a friction means including a friction-shoe whereof the rear part has a greater area of frictional surface than the forward part thereof.

9. In a phonic apparatus, a friction means including a friction-roller and a shoe extending more than half-way around said roller, and composed of two parts hinged together.

10. In phonic apparatus, the combination 125 of a primary and a secondary vibrating means, an intermediate friction device, and means permitting relative movement between one

of said vibrating means and said friction device.

11. In a phonic apparatus, the combination of a primary and a secondary vibrating means, and an automatically-adjustable friction device, the adjustment of said device being effected in response to and being proportional to the friction exerted.

In testimony whereof I have signed this specification in the presence of two subscribing witnesses.

DANIEL HIGHAM.
